CENTER WIRE SCREW ASSEMBLY FOR
RADIO PLUGSHector Rabezzana, Flint, Mich., assignor to A C
Spark Plug Company, Flint, Mich., a company
of Michigan

Application August 7, 1930. Serial No. 473,650

5 Claims. (Cl. 123—169)

This invention relates to ignition devices such as spark plugs for internal combustion engines and to a method of manufacturing the same.

In my pending application Serial Number 418,-
5 573, of which this is a continuation in part, I
have described a spark plug embodying an elec-
trode having as a part thereof a resistance ele-
ment to damp certain electrical oscillations in the
ignition circuit which normally tend to cause in-
terference to radio reception. In the manufac-
ture of these plugs the electrode is cemented in
the insulator core and it has been found that
it is necessary to exercise a great deal of care in
the cementing operation. This cement, which
15 is injected into the bore in a wet or plastic state,
must be given sufficient time, usually several days,
to thoroughly dry out and become set, and since
the resistance element I prefer to use is more
or less porous, it sometimes becomes permeated
20 or partly saturated with the cement which affects
and changes the characteristics of the resistance
element, such change varying with the extent of
saturation and making difficult a uniformity of
product without proper precaution being taken.

25 To provide an improved method of cementing
and assembling the electrode in the insulator,
which will allow the cement to set more quickly
and thereby eliminate excessive absorption of
cement by the resistance element, and result in
30 a more uniform product so as to render more
feasible large quantity production of plugs of the
sort with the use of unskilled labor, and to fur-
ther improve the structure of the plug, particu-
larly from a manufacturing standpoint, are
35 among the objects of the present invention.

To this end there is contemplated in a pre-
ferred, but not necessarily the only embodiment
of the invention, the provision of a central elec-
trode having an intermediate resistance element
40 with end wires projecting from opposite ends
thereof, which may be inserted in the bore of the
insulator and secured by cement that is injected
in two steps with a suitable drying interval there-
between, the outer electrode wire being subse-
45 quently welded or otherwise secured to a binding
post which closes the outer end of the bore after
the last cement injection. By the two-step ce-
ment injection the resistance element is covered
or surrounded by the wet cement at the first in-
50 jection but at this time the end of the bore is not
closed by the binding post and the relatively
small quantity of cement adjacent the resistance
element is therefore directly exposed to the out-
side air. Because of this and since there is only
55 a slight amount of cement involved the cement

can dry out more quickly and before any ap-
preciable amount of it is taken up or absorbed by
the material forming the resistance element.

The invention will be better understood upon
reference to the accompanying drawing where-
in—

Figure 1 is a vertical sectional view showing
the central electrode imbedded in the bore of
an insulator after the first stage of cement in-
jection.

Figure 2 is a sectional view after the second
stage of injection, and

Figure 3 is a fragmentary sectional view of the
upper end of a completed assembly.

Referring to the drawing, the central electrode 70
is shown as consisting of an intermediate resist-
ance element 1 which may be a stick of carbon, or
the like, having affixed on its opposite ends as by
means of cap pieces 2 and 3 respectively, electrode
wires 4 and 5. These wires may be secured to the 75
cap pieces by having enlargements or heads
formed on their inner ends by an upsetting op-
eration and the cap pieces in turn are secured
to the resistance element by contracting or pinch-
ing inwardly the side wall or flanges thereof. 80
The electrode is first inserted in the insulator
core 7, the bore of which is of reduced diameter
at its inner end, as at 8, to receive the inner wire
5 and slightly enlarged, as at 9, to receive the re-
sistance element with the outer end thereof pref- 85
erably screw threaded, as at 10. With the cen-
tral electrode inserted in the bore the inner end
of the insulator may then be placed over the noz-
zle of a suitable cement injection machine for
the injection of the plastic cementitious material 90
12 through the lower end of the bore and up-
wardly around the wire 5 and resistance element
1 until the resistance element is completely cov-
ered, as shown in Figure 1. The parts thus assem- 95
bled are then preferably placed in a suitable dry-
ing oven to set the cement.

After a sufficient interval has elapsed to allow
the cement 12 to set, a second charge of the ce-
mentitious material 13 is injected into the upper
end of the bore and a hollow binding post 15 100
which, as shown in the drawing, is threaded from
opposite ends with an intermediate flange or en-
largement 16, is positioned over the electrode wire
4 and inserted into the wet cement in the upper
end of the bore. This insertion may take place 105
by inter-engaging the screw threads 10 with the
threads of the binding post and screwing the
post down into the wet cement until the collar
16 engages the top of the insulator core, a pack-
ing gasket or ring 17 preferably being interposed 110

- between the collar and core. The engagement of the screw threads is preferably a sloppy one in order that the cement filling the loose spaces will lock the binding post in position. The assembly is once again placed in the drying oven to set the cement last injected. Either before or after the last drying operation the wire 4 and binding post 15 are secured together as by means of a welded joint 18 shown in Figure 3. 80
- 10 1. A metal jacket or shell, indicated by the dotted lines in Figure 2, is later fitted to the insulator core by means of which the spark plug is inserted in the combustion chamber of an engine in the usual fashion. This shell may carry an electrode 85 grounded through the shell and engine and projected in spaced relation with the end of the wire 5 to form a spark gap across which the current may flash when the plug is in use and the ignition wiring connected to the binding post in the conventional manner. The use of the resistance element 1 serves to reduce radio interference by damping the oscillations in the ignition circuit which usually follow the passage of current across the spark gap. 90
- 15 2. The structure described provides a spark plug with a resistance element built in as a part thereof and a method of assembling the parts, has been found to be very effective for high quantity production inasmuch as there is no particular skill 95 required of the operator. By the two step injection of cement the driving out of the moisture in the cement is very much simplified and it has been found further that the characteristics of the resistance element of plugs, assembled in this manner, are not materially affected and that their action in use are more nearly uniform. 100
- 20 I claim:
- 25 1. In a spark plug, an insulator core, a hollow binding post at the outer end of the core, a sectional electrode including as a unitary assembly a porous intermediate section and a pair of end sections projecting from opposite ends of the porous section, and fixing cement surrounding 105 the porous section to hold the electrode in place, one of said end portions projecting beyond the cement and through the hollow post to enable ready connection between the post and porous section after the cement has set and a welded joint between the post and said projecting section. 110
- 30 2. In a spark plug, an insulator core, a sectional electrode within the core including a porous intermediate section, and a pair of end sections projecting from opposite ends of the porous section and beyond the opposite ends of the core, fixing cement surrounding the porous section to hold the electrode in the core, and a binding post adapted for mounting at one end of the core after the cement is set and provided with a hollow portion to receive the adjacent projecting end of the electrode for electrical connection therewith. 115
- 35 3. In a spark plug, an insulator core, an electrode section of porous material, fixing cement securing said section in the core, a binding post at the outer end of the core, and an electrode section connecting the post with the first mentioned electrode section and being initially assembled as a unit with said section and projected beyond the cement to facilitate connection with the post after said cement has set. 120
- 40 4. In a spark plug, an insulator core, a center electrode projecting beyond opposite ends of the core, fixing cement securing the electrode in place, a hollow binding post mounted on the outer end of the core independently of the cement which holds the electrode and adapted to receive the adjacent projecting end of the electrode, and means to electrically connect the post and electrode. 125
- 45 5. In a spark plug, an insulator core, a center electrode projecting beyond opposite ends of the core, fixing cement securing the electrode in place, a hollow binding post associated with the outer end of the core and to receive the adjacent end of electrode and means for securing the electrode and post in electrical connection. 130
